UNITED STATES PATENT OFFICE.

GEORGE G. HUNT, OF BRISTOL STATION, ASSIGNOR OF ONE-HALF TO THE PLANO MANUFACTURING COMPANY, OF PLANO, ILLINOIS.

GRAIN-BINDER.

SPECIFICATION forming part of Letters Patent No. 339,989, dated April 13, 1886.

Application filed November 30, 1883. Serial No. 113,235. (No model.)

To all whom it may concern:

Be it known that I, GEORGE G. HUNT, a citizen of the United States, and residing at Bristol Station, in the county of Kendall and State 5 of Illinois, have invented a certain new and useful Improvement in Grain-Binders, which is fully set forth in the following specification, reference being had to the accompanying drawings, in which—

10 Figure 1 represents an outer side view of a knotter-frame and attachments embodying my invention; Fig. 2, a cross-section of the same, taken on the line $x-x$, Fig. 1, but reversed in position; Fig. 3, a section of the same, taken 15 on the line $y-y$, Fig. 2; Fig. 4, a detail plan of the plunger-bolt and its connections with the cutter.

My present invention relates to that class of 20 grain-binders in which an automatic tripping mechanism is employed for sizing the bundles, and cord is used as the binding material.

The improvements relate to the mechanism for holding and cutting the cord.

I will proceed to describe in detail such 25 parts of a grain-binding machine as are necessary to a full and complete understanding of the construction and operation of my invention as I have embodied it in practical form in a working machine, and will then point out 30 definitely in the claims the special improvements which I believe to be new and wish to protect by Letters Patent.

In the drawings, A represents the knotter-frame or small frame on which the cord holding and tying devices are mounted, and B the main shaft of the binder. On this shaft is 35 mounted the main cam-wheel C, which is provided with gear-section c , as usual, for imparting the required motion to the knotting-hook, which is provided, as usual, with a pinion, d , 40 and is mounted in suitable bearings on the knotter-frame. The cord-holder E is a notched disk, and at one edge runs in a grooved clamp or keeper, F, which in this instance is pivoted, and has an actuating-spring, f , arranged 45 behind it. All these parts are of ordinary general construction, and will be sufficiently well understood without a more particular description in the present instance.

50 I employ a plunger-bolt, G, to operate the

cord-holder; but I make this device of peculiar construction and connect it with the cutter, so that it serves also to operate the mechanism for severing the cord, and I also provide for driving the plunger-bolt positively in each direction of its reciprocating motion. The last-mentioned result I obtain by mounting the plunger-bolt in the arms a of the knotter-frame, which depend from the main shaft, and in such manner as to leave it free to slide back 55 and forth in its bearings. A small cam-wheel, H, is mounted on the main shaft outside of the binder-head, and on the opposite side of the latter to that on which the wheel C is located. The plunger-bolt extends from one of 60 these wheels to the other, and the wheel C is provided with a ring-cam, c' , on its inner face, arranged to bear against the end of the plunger-bolt at that side of the knotter-frame being cut away partly at c^2 , as shown in Fig. 2 of 65 the drawings. The wheel H is also provided with a short cam, h , on its inner face, arranged to act upon the opposite end of the plunger-bolt, and also located so as to correspond substantially with the break or cut-out in the cam 70 c' . Obviously, during the revolution of the main shaft the cam c' will for the greater portion of the time act on the plunger-bolt, and will hold it at the end of its movement toward the small cam-wheel H, its opposite end being 75 in contact with the face of the latter wheel, as shown in Fig. 3 of the drawings. This is an inoperative position of the plunger-bolt, or its position when all the parts actuated by it remain in a state of rest. When, however, 80 in the revolution of the main shaft the cam h is brought into contact with the plunger-bolt, the latter will be reciprocated in the opposite direction, the cut-out in the cam c' permitting this movement, and this motion of the 85 plunger-bolt operates the cord-holder and the cutter, as I will now describe, the parts of course being arranged and timed to produce these operations at the proper moment. The ends of the plunger-bolt are preferably provided with rollers for the purpose of reducing friction. The plunger-bolt G has an arm or branch, g , which, when the parts are in position on a binder, extends downward by one 90 side of the arms of the knotter-frame and passes 95 100

beyond and outside of a cross piece or bar, a' , which joins the lower or depressed ends of the sidearms, a , of the knotter-frame. This branch g is bent so as to pass along the cross-piece a' 5 on the outside thereof to the opposite side of the knotter-frame, as shown in Figs. 3 and 4 of the drawings.

The cord-holder E is provided at its back or underside with a ratchet-wheel, e . A pawl, 10 I , is pivoted to the depending arm of the plunger-bolt and arranged to engage with the teeth of the ratchet-wheel, being provided with any suitable spring, i , which operates to hold it in such engagement. As the plunger-bolt is driven inward toward the wheel C by the cam on the wheel H , the pawl is carried bodily in the same direction, thereby rotating the disk cord-holder at the proper time, and for the usual purpose of clamping the cord. 15 A spring-stop, e' , is fastened to the knotter-frame and arranged to engage at its other end with the ratchet-wheel for the purpose of preventing any back movement of the cord-holder. The pawl, it will be noticed, is attached by a single firm pivot to a rigid part 20 of the plunger-bolt, and its form and location are such that the direction of the toe is nearly parallel with the plunger-bolt, and so the movement of the toe of the pawl is in a line 25 nearly parallel with the movement of the plunger-bolt, and substantially tangential to the ratchet-wheel, its spring serving to keep it engaged with the ratchet-wheel, however, during this movement. At the extreme outer end 30 of the arm g of the plunger-bolt there is a short stud or boss, g^2 , (shown in dotted lines in Fig. 4, of the drawings,) above which is an angular plate, J , which is pivoted at one corner to the knotter-frame, and is provided with a 35 dial slot, j , outside the pivot. The cutter J' is attached to this plate, which serves as its holder, and the plate is connected to the stud g^2 by a pin, g' , passing through the radial slot, as shown in Fig. 4 of the drawings. Obviously, the reciprocating movement of the plunger-bolt will vibrate this plate, and so give a 40 corresponding motion to the cutter-edge sufficiently to cut the cord, and is arranged to do this at the proper moment. The cutter and 45 its holder, obviously, may be made in a single piece, if desired, instead of two pieces, as here shown, the gist of the improvement being the construction and arrangement of the devices whereby the cutter is operated directly and 50 positively in all of its vibrations by the plunger-bolt.

I have shown and described above in detail the construction and arrangement of special devices by means of which I have carried my 55 invention into practical operation; but I do not wish to be understood as limiting myself to this particular construction and arrangement of devices in details, for obviously changes may be made in this respect, and yet the main 60 features of the invention be retained.

In providing means for reciprocating the

plunger-bolt positively I avoid the use of all springs, against the force of which the plunger-bolt must be active in the ordinary construction, and there is no resistance to be overcome in the movement of this bolt, except the slight friction in its bearings and that occasioned by the mechanism which it is employed to operate. It will be seen, too, that the mechanism for operating the cord-holder is very 70 simple and so constructed and arranged that it must act with certainty and without liability to disarrangement. Here, too, there is no resistance of springs to overcome. The same is true of the cutter. It is operated positively 75 by a simple connection with the plunger-bolt and without the resistance of springs to be overcome, and by its connection through the plunger-bolt with the other devices must work at the proper time. I obtain from my improvements, then, simplicity of construction, 80 certainty of action, and a reduction of resistance to be overcome by the motive force.

In an earlier application of mine, No. 95,342, filed May 18, 1883, there are some devices 90 somewhat similar to those here shown and described. In the said earlier application, however, the cord-holder pawl or pawl-support is loose on the plunger-bolt, being connected to the latter by an eye, which provides for movement of this piece on the bolt itself. In the present case it will be noticed that the pawl is pivoted to a rigid piece projecting from the plunger-bolt, and the latter is moved positively in both directions. I here disclaim all devices shown in the said earlier application as 95 a part of my present improvement.

Having thus described my invention, what I claim as new, and desire to secure by Letters Patent, is--

1. In a grain-binder, the knotter-frame, in combination with the plunger-bolt mounted loosely in bearings on said frame, and revolving cams arranged to operate alternately on opposite ends of the bolt to reciprocate the latter positively in each direction, substantially as described.

2. The plunger-bolt mounted in bearings, in combination with the cam-wheel C , provided with the broken ring-cam c' , and the wheel H , provided with the short cam h , substantially as and for the purposes set forth.

3. The knotter-frame, in combination with the reciprocating plunger-bolt mounted thereon, the rotating cord-holder arranged some 120 distance below the plunger-bolt, and the bent pawl pivoted directly to a projection of the plunger-bolt, substantially as and for the purposes set forth.

4. The knotter-frame, in combination with 125 the reciprocating plunger-bolt mounted on the upper portion thereof, the disk cord-holder arranged some distance below the plunger-bolt and provided with a ratchet, and the spring-pawl pivoted directly to a projection 130 of the plunger-bolt and bent to cause the toe to move in a straight line about tangential to

the ratchet-wheel, substantially as and for the purposes set forth.

5. The reciprocating plunger-bolt, in combination with cord-holder, the actuating-pawl of the cord-holder connected to said bolt, and the cord-cutter pivoted to the knotter-frame and also connected to the plunger-bolt, whereby the reciprocation of the latter operates both the cord-holder and cutter, substantially as and for the purposes set forth.

10. The reciprocating plunger-bolt provided with the bent extension, substantially as specified, in combination with the angular pivoted cutter, substantially as and for the purposes set forth.

15. The reciprocating plunger-bolt provided with the extension g , carried downward and across the knotter-frame, in combination with the stud g^2 upon its outer end, and pivoted 20 angular plate J, provided with the slot j , through which a pin, g' , extends to connect the plate to the stud, and the cutter J', attached to the said plate, substantially as and for the purposes set forth.

8. The knotter-frame, in combination with 25 the reciprocating plunger-bolt mounted loosely in bearings thereon, devices arranged to operate alternately on opposite ends of said bolt to reciprocate it positively, and a vibrating cord-cutter pivoted to the knotter-frame and 30 connected with the plunger-bolt, whereby it is moved positively by the latter, substantially as and for the purposes set forth.

9. The knotter-frame, in combination with the reciprocating plunger-bolt mounted loosely 35 in bearings thereon, devices arranged to operate alternately on opposite ends of said bolt to reciprocate it positively, a vibrating cord-cutter pivoted to the knotter-frame and connected with the plunger-bolt, a cord-holder, 40 and a pawl on the plunger-bolt for operating the cord-holder, substantially as and for the purposes set forth.
